UNITED STATES PATENT OFFICE.

ANDREW J. KERSHNER, OF MAYBEURY, WEST VIRGINIA.

PACKAGE-TIE.

1,177,633.

Specification of Letters Patent.

Patented Apr. 4, 1916.

Application filed March 18, 1914. Serial No. 825,577.

To all whom it may concern:

Be it known that I, ANDREW J. KERSHNER, a citizen of the United States, residing at Maybeury, in the county of McDowell and State of West Virginia, have invented new and useful Improvements in Package-Ties, of which the following is a specification.

An object of the invention is to provide a simple and effective package tie for use in 10 securing the wrappings about packages or for securely holding together a two part box or the like.

The invention embodies, among other features, the provision of a simple and effective tie which, when applied to the package, can be so arranged as to take up any slack so that the tie will fit snugly around the package and properly secure the same in the event that the package embodies a two part 20 box or in the event that the package includes a wrapping wrapped around the box or the like and which wrapping should be neatly and snugly held in wrapped position about the box.

One of the primary uses of my invention is in connection with trunks and in which the invention affords an additional means of securing the cover of the trunk to the body thereof aside from the usual lock, 30 while at the same time, the invention, when made of rope or leather, will act as a cushion for the trunk to deaden any shock or jar to which the trunk may be subjected when the same is dropped rather heavily to the floor 35 or ground when unloading the trunk from a wagon.

In the further disclosure of the invention reference is to be had to the accompanying drawings, constituting a part of this specification, in which similar characters of reference denote corresponding parts in all the views, and in which:

Figure 1 is a perspective view of a package or trunk having my device applied 45 thereto, the same being in normal or slack position; and Fig. 2 is a similar view showing the device tightened up around the package or trunk.

Referring more particularly to the views, 50 I disclose a package 10 of a substantially rectangular construction and around which extend a series of bands 11 preferably arranged transversely to the longitudinal plane of the package 10, as shown, and the 55 said bands are preferably equi-distantly spaced apart throughout the length of the

package. Each band is provided with opposed upper and lower diamond shaped portions 12, with the upper diamond shaped portion of each band lying against the top 60 of the package and the lower diamond shaped portion of each band lying against the bottom of the package. The diamond shaped portion of one band is connected with the diamond shaped portion of the next 65 adjacent band by a connecting member 13, as shown, and secured to the diamond shaped portions 12 of the outermost band on the package, and at each end of the package, are suitable straps 14 having buckles 15 70 thereon.

Now it will be understood that the bands 11 are preferably made of rope or leather and that the diamond shaped portions 12 thereof are made of the same material as are 75 also the connecting members 13 and straps 14. The straps 14 are initially open or disconnected from the buckles thereof so that the band can be slipped over the package, and it will be apparent that when the bands 80 are initially slipped over the package, the diamond shaped portions will be elongated transversely to the longitudinal plane of the package, or, in other words, will be elongated in the plane of the bands of which they form portions. Now when the straps 14 are connected with the buckles 15 and each strap is successively tightened it will 85 be apparent that the configuration of the diamond shaped portions 12 will be changed 90 as shown in Fig. 2, so that the diamond shaped portions will be elongated in the longitudinal plane of the package, or, in other words, will be elongated in the plane of the connecting members 13, thus taking up 95

any slack in the bands 11 and the connecting members 13 as the pull on the straps 14 is increased so that when the straps have been tightened to their limit the entire structure will closely and snugly fit around the package as shown. Should for any reason one of the flexible members 12 break during the tightening of the device about the package, a piece of ordinary cord or the like may be easily and quickly threaded through the 100 eyes 13' of the bands 11 and the connecting elements 13, as a substitute for one of these flexible elements and functionate in the same manner and with the same advantages as said element.

It will thus be seen that the entire device 105 consists simply of a series of bands having

diamond shaped portions normally elongated in the plane of the bands with connecting members for the adjacent diamond shaped portions, and straps so arranged that when they are tightened the diamond shaped portions will be elongated in the plane of the connecting members and the major axes of the diamond shaped portions will become the minor axes thereof.

10 As stated heretofore, the invention is adapted for use with all kinds of packages, but is conveniently and preferably adapted for use on trunks or other heavy baggage such as large boxes and the like, and in 15 which it is desired to provide an additional securing means that will also tend to act as a protection for the trunk or box, as mentioned.

Having thus described my invention, I 20 claim:

In a package tie, a plurality of spaced parallel bands, each terminally provided with eyes disposed adjacent the opposite longitudinal edges of the package, an end-

less loop of flexible material passed through 25 said eyes of each band, a plurality of aligned connecting strips interposed between each pair of loops and arranged to lie in a plane with the longitudinal center of the package, an eye on each end of the strips through 30 which the adjacent side of each loop is passed, an additional strip projecting from the final side of the two outermost loops, a buckle carried by the free end of each of the last mentioned strips, and a strap extending 35 longitudinally about the package and having its free ends adjustably associated with said buckles to cause said loops to assume a diamond shaped outline, whereby to simultaneously tighten said bands transversely of 40 the package with the tightening of said strap.

In testimony whereof I affix my signature in presence of two witnesses.

ANDREW J. KERSHNER.
